UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

CONNECTING JOINT.

Application filed April 10, 1919. Serial No. 289,093.

To all whom it may concern:

Be it known that I, ARTHUR O. AUSTIN, a citizen of the United States, residing at Barberton, in the county of Summit and 5 State of Ohio, have invented certain new and useful Improvements in Connecting Joints, of which the following is a specification.

My invention relates to the construction 10 of joints for holding various materials together, and has for its object the provision of connecting joints having means for controlling the distribution of stresses transmitted and which shall be of improved construction and efficiency.

The invention is exemplified in the combination and arrangement of parts shown 15 in the accompanying drawings and described in the following specification. The invention is more particularly pointed out in the appended claims.

In the drawings—

Fig. 1 illustrates one embodiment of the invention as applied to an insulator;

25 Fig. 2 is a section on line 2—2 of Fig. 1;

Figs. 3, 4 and 5 are diagrammatic sectional views through different forms of joints illustrating various modifications of the invention;

30 Fig. 6 is a fragmentary elevation showing still a different form of the invention.

In order that the present invention may be best understood, its application to various forms of electrical insulators has been illustrated, but it is understood that the invention is applicable to a large variety of articles other than insulators. It is especially useful where one of the members connected by the joint embodying the invention 35 is of material more or less brittle in its nature. Electric insulators are commonly made of porcelain, or other vitreous substances, and a joint constructed in accordance with the present invention is especially applicable to 40 material of this character.

In Fig. 1 of the drawings, the numeral 15 designates a tubular insulator which may be made of porcelain, or other suitable material, while the numeral 16 is a metallic end 45 cap secured to the tube 15 for connecting the tube either with the load which it carries, or with its support. The end cap 16 may be tapered as shown in the drawing or may have its sides straight as conditions 55 may require. In my prior Patent No.

1,284,975 issued November 19, 1918 I have described a form of sanded joint for connecting parts of insulators together, and the present invention is an improvement and amplification of the joint shown in that 60 patent. In preparing the end of the insulator 15 for its connection with the cap 16, the portion of the insulator which is to form the joint is coated with a glaze, and while the glaze is yet moist, small grains of material are distributed over the coated surface and adhere to the moist glaze. The grains are preferably small particles of the clay of which the porcelain tube 15 is composed, for the reason that this clay has the 65 same shrinkage in burning and afterwards will have the same coefficient of expansion as the material of the tube 15 itself. It is, of course, possible to use grains of sand, or other substances in place of particles of clay. 70 When the insulator thus prepared is burned in the usual manner, the grains distributed over the surface become fixed to the material of the insulator by the glaze which is hardened in burning and form a roughened 75 surface for the joint. As described in my prior patent, the points of these grains will protrude to a greater or less extent from the glaze, and before the metallic cap 16 is cemented on, a coating of some elastic material, such as wax or paraffine is spread 80 upon the sanded surface in a manner to leave the points of the grains protruding. The cap is then secured in place, as shown in Fig. 1, by cement indicated at 17, which 85 completes the connection between the cap and the insulator, as explained in the patent referred to, and the joint thus made has a 90 certain degree of elasticity which tends to prevent breaking of the insulator under the 95 various stresses to which it is subjected.

In Fig. 3 of the drawings, the particles with which the insulator surface is covered, and which will be hereafter referred to as sand grains, are shown diagrammatically at 100 18. The glaze by which the grains are held to the porcelain is indicated at 19, and the filling of yielding material is shown at 20. It will be noted from the drawings that the coating of yielding material 20 is considerably thicker adjacent the edge of the cap 16 105 and is graded toward the end of the insulator 15 until it becomes very thin at the inner end of the joint. It will thus be seen that the grains 18 adjacent the edge of the cap 16 110

will have their points only imbedded in the cement 17. This will constitute a comparatively elastic connection between the cap and the insulator at this point, for the reason that the grains 18 will act as struts, and will yield under stress between the cap and the insulator. The amount of yielding, of course, is very small, but as compared with the strain produced by a load upon the porcelain 15, it is relatively considerable. At the inner end of the joint there is a comparatively rigid connection between the cap and the insulator, for the reason that practically the entire sand grains are imbedded in the cement. Between the two points the elasticity of the union gradually grades from one extreme to the other.

It is thought that the purpose of this graded elastic joint will be readily apparent. If there were an absolute rigid connection between the cap 16 and the insulator 15 at the edge of the cap, then the load upon the insulator would all be transmitted to the cap at this point. This would place undue stress upon the cement at this point, tending to cause the joint to fail, and would also subject the material of the insulator 15 to a greater breaking stress than that produced by the graded joint. It will be readily understood that the cap 16 must grip the insulator 15 when a load is placed upon the insulator sufficiently tight to prevent the insulator from slipping out of the socket formed by the cap. If there were no yielding in the joint between the cap and the insulator, the stress of the load would all be taken up at the edge of the insulator, and the gripping force of the cap would all fall at this point, producing in addition to the stress in the insulator, due to the load upon it, a shearing stress adjacent the edge of the cap. Under tests insulators which have rigid connection with their caps are found to fail at this point and to fail along lines of the resultant between the tensional load upon the insulator and the shearing stress produced by the cap. Where a graded elastic joint is provided only a small portion of the load is transmitted to the cap at its outer edge and the insulator is permitted to yield under the tension upon it, so that other portions of the load are transmitted to the cap at the various points along the joint. Thus the stress of the load is distributed throughout the joint, and the shearing stress on the insulator necessary to hold the insulator in place is also distributed through the length of the material 15 surrounded by the joint.

In Fig. 4 of the drawings, the grains 18 are graded in size from a position adjacent the edge of the cap 16 to the inner end of the joint, and the coating material 20 is also graded in the same manner as in Fig. 3. The grading of the grains adds to the effect produced in Fig. 3, for the reason that the large

grains at the edge of the cap constitute longer struts than the small grains at the inner end of the joint, and consequently exhibit a greater elasticity than the smaller grains.

In Fig. 5 the grains 18 are shown as of uniform size throughout the joint, and the coating is also made uniform, but the cap 16 is peripherally corrugated, as shown at 21, the corrugations increasing from the end of the insulator toward the edge of the cap. In this way the cap itself is made elastic so that it will yield adjacent its edge in the direction of the length of the insulator when stress is placed upon the insulator and hold more and more rigidly toward the inner end of the joint.

In Fig. 6 the cap 16 is slotted at its edge for a distance inwardly, as shown at 22. This slitting of the cap produces a yielding grip upon the insulator at the edge of the cap, the yielding of which is greatest at the end of the tongues formed by the slits 22, and gradually decreases toward the inner end of the joint. It will be understood that other expedients may be used for producing a graded elastic joint between the two members connected, and that various combinations of the means illustrated in the drawings may also be employed.

While the method described of securing the grains to the insulators is the one at present preferred it will be understood that the grains may be held in place by various adhesive materials such as varnish for instance, and this will permit the sanding to be placed on the surface of finished insulators. It will also be apparent that the same kind of graded connection is applicable to a large variety of forms of insulators as for instance the ordinary pin type insulators and suspension insulators having caps and pins or caps or pins only. The graded projections as well as the graded coating may also be applied to either the metal or insulator member or to both, and may be used for connecting two insulator members together and even for connecting two metallic members.

I claim:

1. In combination, a pair of members having overlapping portions secured together at points distributed along said overlapping portions by connecting material, said material being arranged to permit an elastic movement between said members, the elasticity of said connection being graded to different amounts along said overlapping portions.

2. In combination, a pair of members having overlapping portions, and means for elastically connecting said overlapping portions together, the degree of elasticity of said connection being progressively varied along said connection between said members at different positions along the overlapping

portions thereof to distribute the force transmitted from one to the other of said members.

3. In combination, a pair of members to be connected together, and means for forming a graded elastic joint between said members.

4. In combination, a pair of co-operating members having overlapping surfaces, one of said surfaces being provided with projections thereon, means for cementing said surfaces to one another, and means for protecting portions of said projections from engagement with said cementing means, said protecting means being arranged to cover progressively varying amounts of said projections along the overlapping portions of said members.

5. A joint for connecting two members together comprising a plurality of projections distributed upon the surface of one of said members, and means for connecting said projections with a surface of the other of said members, said connecting means being arranged to engage varying portions of said projecting means to form a progressively graded elastic joint between said members.

6. In combination, a member composed of relatively fragile material, an attaching member, and means for connecting said members together, said connecting means being arranged to form an elastic joint between said members, the elasticity of which joint progressively varies from one portion thereof to another.

7. In combination, a pair of co-operating members for supporting a load, and means for connecting said members together to form a joint for transmitting the stress of said load from one member to the other, said connecting means being arranged to permit elastic yielding between said members at one point in the connection between them and to permit, between said members, at other points, elastic yielding which varies progressively from said first-mentioned point, along said joint.

8. In combination, a relatively fragile member and a supporting member therefor, and means for connecting said members to form a joint to transmit the stress of a load from one of said members to the other, said connecting means being arranged to form a connection between said members having a progressively decreasing elasticity from a point along said fragile member toward the end thereof.

9. In combination, a member having spaced projections on the surface thereof, a second member adjacent said surface and secured thereto by interposed cement, and a coating of yielding material for partially covering the projections on said surface, said coating being arranged in a progres-

sively varying thickness over said surface.

10. In combination, a member having spaced projections on the surface thereof, and a second member arranged adjacent said surface and secured thereto by connecting material, the projections on said surface being arranged in progressively varying size along said surface.

11. In combination, a member having spaced projections upon a surface thereof, a second member adjacent said surface and secured thereto by connecting material, the projections on said surface being progressively graded in size along said surface, and a coating of yielding material on said surface for protecting portions of said projections from said connecting material, said coating being arranged in progressively varying thickness along said surface.

12. In combination, a member composed of relatively fragile material, spaced projections distributed over a portion of the surface of said member, a second member arranged in overlapping relation to the surface of said first-mentioned member, connecting material for securing said members together, and a coating of yielding substance between said connecting material and the surface of said first-mentioned member, the thickness of said coating being so varied so as to protect progressively differing amounts of said spaced projections from engagement with said connecting material.

13. In combination, a member having projections distributed over a portion of its surface adjacent one end thereof, a second member arranged in overlapping relation with said portion of the surface of said first-mentioned member, and connecting material for securing the overlapping portions of said members together, said connecting material being arranged to hold the projections on the surface of said first-mentioned member more firmly imbedded therein adjacent the end of said member than at points spaced from the end thereof to provide a joint between said members having progressively varying elasticity along said joint.

14. In combination, a relatively fragile member having a securing member attached to one end thereof, and securing means for holding said members together, said securing means being arranged to constitute an elastically yielding joint between said members which gradually decreases in elasticity from the extremity of said securing member toward the extremity of said relatively fragile member.

15. In combination, a relatively fragile member having a securing member attached thereto and arranged to overlap a portion of the extremity of said relatively fragile member, spaced projections upon the surface of said relatively fragile member, a coating of yielding material on said surface in

- which said projections are partially imbedded, said coating being arranged to vary in thickness to permit varying amounts of said projections to extend therefrom, and a filling of cement between said members and engaging the extending portions of said projections and forming with said projections a progressively varying elastic connection between said members.
16. An insulator having an end cap thereon and means for connecting said end cap to said insulator to form a joint therebetween that will permit of relative yielding between said cap and insulator when said joint is subjected to stress, the amount of yielding thus permitted being graded to vary for different positions along said joint.
17. An insulator having an end cap thereon and means for connecting said cap to said insulator said connecting means being arranged to permit relative yielding between said cap and insulator the amount of yielding thus permitted being greatest at the free edge of said cap and decreasing in a direction away from said edge toward the end of said insulator.
18. An insulator having an end cap thereon connected with said insulator by a sanded joint to permit yielding between said cap and insulator said joint being graded to vary the amount of yielding between said members so that the amount of yielding decreases from a position adjacent the edge of said cap toward the end of said insulator.
19. An insulator having a connecting member surrounding a portion of an extremity thereof, spaced projections secured to the surface of said insulator contiguous to said connecting member means for securing said connecting member to the projections on said surface to form a yielding joint to permit relative movement between said insulator and said connecting member, the points of connection between said projecting members and said securing means being spaced progressively varying distances from the bases of said projecting members to permit of progressively increasing amounts of movement between said insulator and said connecting member at different points in the joint between said members.
20. An insulator having a connecting member secured thereto, spaced projections distributed over the surface of said insulator adjacent a surface of said connecting member means for securing said projections to said connecting member and a coating of yielding material for protecting a portion of the bases of said projections from said securing means, the thickness of said coating being varied for different positions on said surfaces to permit different proportions of said projections to engage said securing means, thus providing a graded yielding joint between said insulator and connecting member with the amount of yielding progressively decreasing from a position adjacent the extremity of said connecting member toward the end of said insulator.
21. An insulator having a connecting member secured thereto, spaced projections distributed over the surface of said insulator adjacent a surface of said connecting member, and means for securing said projections to said connecting member said projections being graded in size to provide for different amounts of movement between said insulator, and said member at different positions in said joint.
22. In combination, a pair of members having overlapping portions and elastic means interposed between said overlapping portions for securing said members to one another, the elasticity of said securing means being graded to vary for different positions along the joint formed thereby.
- In testimony whereof I have signed my name to this specification on this 3rd day of April A. D. 1919.
- ARTHUR O. AUSTIN.
